US00D690194S

(12) **United States Design Patent**
Snedden et al.

(10) **Patent No.:** **US D690,194 S**
(45) **Date of Patent:** **** Sep. 24, 2013**

(54) **CONTAINER**

(75) Inventors: **Craig R. Snedden**, Culver City, CA (US); **Gandhi B. Sifuentes**, West Covina, CA (US); **Eric Wexler**, Salinas, CA (US); **Gurmail Mudahar**, Salinas, CA (US)

(73) Assignees: **Direct Pack, Inc.**, Sun Valley, CA (US); **Tanimura & Antle Fresh Foods, Inc.**, Salinas, CA (US)

(**) Term: **14 Years**

(21) Appl. No.: **29/418,009**

(22) Filed: **Apr. 11, 2012**

(51) **LOC (9) Cl.** **09-03**

(52) **U.S. Cl.**

USPC **D9/425**

(58) **Field of Classification Search**

USPC ..... D9/414, 416, 417, 419, 424, 425, D9/430, 431, 432, 761; D7/538, 549, 550.1, D7/601–603, 605, 629; 220/23.4, 23.6, 266, 220/281, 315, 318, 500, 659, 669, 674, 675, 220/696, 752, 760, 790, 793, DIG. 12, FOR. 117; 229/105, 117.09, 117.26, 189, 406, 229/407, 902, 905, 915.1; 206/499, 508, 206/557; D3/276

(57) **CLAIM**

The ornamental design for a container, as shown and described.

DESCRIPTION

FIG. 1 is a top perspective view of a container, showing our new design;

FIG. 2 is a bottom perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The hinge and lid retention features shown in broken lines are unclaimed environment, and form no part of the claimed design.

1 Claim, 8 Drawing Sheets
